UNITED STATES PATENT OFFICE.

JONAS NORTHRUP, OF HOPEDALE, MASSACHUSETTS, ASSIGNOR, BY MESNE ASSIGNMENTS, TO DRAPER CORPORATION, OF HOPEDALE, MASSACHUSETTS, A CORPORATION OF MAINE.

LOOM.

Application filed August 16, 1921. Serial No. 492,734.

The present invention relates to an improvement in looms, more particularly automatic weft replenishing looms.

It sometimes happens in replenishing the weft in automatic looms that the bobbin inserted in the shuttle by the weft replenishing mechanism is not correctly presented nor securely held in the shuttle, with the result that on the beat of the lay to the rear after replenishment, the bobbin moves from its position in the shuttle to some other position, sometimes jumping out above or below the shuttle, and sometimes assuming a position at right angles to the shuttle. This sometimes prevents picking of the shuttle and then when the lay beats forward again, the bobbin strikes against the hopper and suddenly arrests the lay and stops the loom. While this is objectionable in ordinary belt driven looms because of the wear on the belt and the liability of injury to the lay and to the loom as a result of this accident, it is a more serious matter in a motor driven loom, for in such case it might happen that the lay would be arrested in its forward movement before the dagger on the protector mechanism had struck the frog to knock off the loom, with the result that the loom would be stopped and, the electric motor being held stationary, the motor might be burned out.

The object of the invention is to produce an automatic loom having provision for preventing a mis-inserted bobbin from assuming such a position as to stop the lay on its forward movement before the protector mechanism would be operated. To this end the invention consists in the loom herein-after described and particularly defined in the claims.

In the accompanying drawings illustrating the preferred form of the invention, Fig. 1 is a sectional elevation taken at right angles to the lay, showing an end view of the hopper and associated parts embodied in a loom; Fig. 2 is a longitudinal, vertical, sectional elevation of the lay with a misplaced bobbin and shuttle therein; Fig. 3 is a plan view of the lay and a portion of the hopper taken on the line 3-3, Fig. 1; and Fig. 4 is a diagrammatic plan of a loom showing the frame, the lay, the hopper and motor.

The illustrated embodiment of the invention is described as follows: The hopper stand or plate 1 is supported on the bracket

or foot 2 on the breast beam in the usual manner. In Fig. 1 the lay beam 3 and the shuttle 4 are shown in their rear position. Supported on the lay in the usual manner is the dagger 5 of the protector mechanism adapted to cooperate with the frog 6, which operates to knock off the loom, in case it is a belt driven loom, or, to open the clutch, in case it is a motor driven loom. In dot and dash lines in Fig. 1 is shown at 4 the position of the shuttle when the lay is on its forward center, and the dash and dot circle shows the bobbin 7 when it is first inserted in the shuttle 4. The bobbin 7 in passing from the hopper into the shuttle 4 presses rearwardly the bobbin support 10, which is pressed forward into its normal position by the spring 11, as is illustrated in the patent granted to me March 19, 1918, No. 1,259,768. The bobbin support 10 is carried by the block 12, as is shown in said patent. On the rear end of this block is secured a bobbin butt cover 13, which has a vertical flange 14 by which it is secured to the end of the block 12. It is also provided with a plate 15, extending rearwardly as shown in Figs. 1 and 3, which is braced in its position by the flange 16 at its left-hand end, as viewed in Fig. 3. When a bobbin is inserted in the shuttle, it is inserted through the open top of the shuttle box and occupies the dash and dot line position indicated in Fig. 3, and as the lay moves rearwardly, the butt of the bobbin moves under the block 12, and then under the bobbin butt cover 13, so that the bobbin is prevented from jumping out of the shuttle in case it shall not have been properly placed in the shuttle and secured therein by the shuttle spring.

It will be understood that with a loom not provided with the present invention in case the bobbin were misplaced in the shuttle, and the attempt had been made to pick it away from the weft replenishing side of the loom to the opposite side, it became misplaced, it might assume a vertical position, as illustrated in dash and dot lines in Fig. 1, thereby arresting the shuttle and preventing the pick and operating to arrest the lay on its forward beat by the engagement of the bobbin with the block 12 of the hopper plate before the dagger 5 of the protector mechanism would reach the frog 6, and that this would stop the loom. In case

of a belt driven loom this would cause the belt to slip on the driving pulley; in the case of a motor driven loom, as illustrated in Fig. 4, it would create conditions favorable for burning out the motor. In Fig. 2 a shuttle is shown in position arrested on its first pick away from the replenishing side of the loom with the bobbin held in depressed position under the bobbin butt cover, and while this would arrest the shuttle and prevent the first pick from taking place, it would not stop the forward beat of the lay because the bobbin would be held down by the bobbin butt cover, with the result that the protector mechanism would stop the loom without injury to the belt or motor.

Fig. 4 is a diagrammatic representation of a motor driven loom to which the invention is preferably applied, because the injury liable to be suffered by the motor in the case of a motor driven loom is much greater than that to which the loom would be liable in case it were belt driven. The frame of the loom is indicated at 20, the breast beam at 21, the lay at 3, the motor at 22, and the hopper or battery at 23.

Viewed in its broader aspects the present invention contemplates an automatic weft replenishing power driven loom provided with means for preventing a bobbin from assuming a position in the shuttle on the rearward motion of the lay after weft replenishment acting to stop the loom on the next forward beat of the lay and more specifically an electric motor driven loom, having such means so as thereby to prevent endangering the motor by stopping the loom without opening the motor clutch.

Having thus described the invention, what is claimed is:

1. An automatic bobbin supply loom having, in combination, a lay, bobbin supply mechanism, means for actuating the loom, and means mounted on a stationary part of the loom acting during the first rearward movement of the lay after replenishment, upon the bobbins tending to assume a position to prevent picking, to prevent the bob-

bin from assuming a position on such rearward movement liable to stop the loom by arresting the lay on the next forward beat. 50

2. An automatic bobbin supply loom having, in combination, a lay, an open top shuttle box, bobbin supply mechanism, means for actuating the loom, and stationary means 55 for covering the bobbin butt while in the shuttle box on the weft replenishing side of the loom at all positions of the lay.

3. An automobile bobbin supply loom having, in combination, a lay, an open top shuttle box bobbin supply mechanism, means for actuating the loom, said bobbin supply mechanism being provided with a portion for covering the shuttle butt while the bobbin is in the shuttle box on the weft replenishing side of the loom at all positions of the lay. 65

4. An automatic bobbin supply loom having, in combination, a lay, bobbin supply mechanism, comprising a hopper plate, said 70 hopper plate being provided with bobbin butt covering means for covering the bobbin butt while it is in the shuttle on the weft replenishing side of the loom at all positions of the lay. 75

5. An automatic bobbin supply loom having, in combination, a lay, bobbin supply mechanism, protector mechanism, means for actuating the loom, and means mounted on a stationary part of the loom acting during 80 the first rearward movement of the lay after replenishment to prevent the bobbin from assuming a position on such movement of the lay liable to stop the loom by striking a stationary part of the loom on the next 85 forward beat.

6. An automatic bobbin supply loom having, in combination, a lay provided with an open-top shuttle box, bobbin supply mechanism, means located above the butt of the 90 bobbin before the shuttle is picked from the box for preventing the bobbin from rising out of the box after the lay has moved rearwardly from its front center position.

JONAS NORTHROP.
